(57) CLAIM

The ornamental design for a personal tactical organizer vest, as shown and described.

DESCRIPTION

FIG. 1 is a perspective view of a personal tactical organizer vest, showing the new design;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is a bottom view thereof; and,

FIG. 8 is an environment of use view thereof.

The broken lines shown on the personal tactical organizer vest are stitch lines and form a part of the claimed design. The broken lines shown in FIG. 8 represent environment and form no part of the claimed design.
